DESIGN FOR A HANDBAG

Irving Pichel, New York, N. Y.

Application June 9, 1944, Serial No. 113,931

Term of patent 7 years

(Cl. D87—2)

To all whom it may concern:

Be it known that I, Irving Pichel, a citizen of the United States of America, residing in the city of New York, county of New York, and State of New York, have invented a new, original, and ornamental Design for a Handbag, of which the following is a specification, reference being had to the accompanying drawing, forming part thereof.

The figure is a perspective view of a handbag showing my new design.

The opposite side (not shown) is substantially the same as the side shown.

The dominant feature of my design resides in the portions shown in full lines.

I claim:

The ornamental design for a handbag, substantially as shown and described.

IRVING PICHEL.
